United States Patent

Des. 239,669

Patented Apr. 27, 1976

239,669

FOOT SOCK

Raymond Jacobs, New York, N.Y., assignor to Kalso
Systemet, Inc., New York, N.Y.

Filed Aug. 16, 1974, Ser. No. 498,087

Term of patent 14 years

Int. Cl. D2—04

U.S. Cl. D2—330

Fig 1

Fig 2

Fig 4

Fig 3

FIG. 1 is a front and right side perspective view of a foot sock showing my new design;

FIG. 2 is a front elevational view;

FIG. 3 is a rear elevational view; and

FIG. 4 is a side elevational view.

The pattern partially shown on the upper portion of the foot sock is continuous over this portion of the foot sock.

I claim:

The ornamental design for a foot sock, substantially as shown and described.
